DESIGN FOR PAPER OR THE LIKE

Angela Straeter, Holmes, N. Y., assignor to Frav-essi-Lamont, Inc., New York, N. Y., a corporation of New York

Application February 10, 1945, Serial No. 117,875

Term of patent 7 years

(Cl. D59—2)

To all whom it may concern:

Be it known that I, Angela Straeter, a citizen of the United States, residing at Holmes, in the county of Dutchess and State of New York, have invented a new, original, and ornamental Design for Paper or the like, of which the following is a specification, reference being had to the accompanying drawing, forming part thereof.

The figure is a plan view of a piece of paper or the like, showing my new design.

The dotted lines on the drawing outline the design unit which is repeated in regular succession as indicated by the extensions beyond the unit boundary.

I claim:

The ornamental design for paper or the like, as shown and described.

ANGELA STRAETER.
